UNITED STATES PATENT OFFICE.

CARL H. HAUGK, OF NEW YORK, N. Y.

CIGAR-BUNCHING MACHINE.

SPECIFICATION forming part of Letters Patent No. 416,911, dated December 10, 1889.

Application filed September 12, 1888. Serial No. 285,192. (No model.)

To all whom it may concern:

Be it known that I, CARL H. HAUGK, of the city, county, and State of New York, have invented certain new and useful Improvements 5 in Cigar-Bunching Machines, of which the following is a specification.

This invention relates to an improved cigar-bunching machine in which so-called "long filler" is used, and in which the tobacco is 10 cut into the shape of a cigar and transmitted to the rolling-table, where the binder is wound around the same, the binder being transferred to the rolling-table from a binder-table by 15 pneumatic or other means, so that long-filler cigar-bunches of perfect shape and quality can be quickly and cheaply turned out.

The invention consists of certain combinations of parts and details, as will be fully described hereinafter, and finally pointed out 20 in the claims.

In the accompanying drawings, Figure 1 is a side elevation of my improved cigar-bunching machine, parts being broken out and others shown in section. Fig 2 is an enlarged end elevation of the same, parts being 25 in section on the line $x-x$, Fig. 1, and other parts being broken out. Fig. 3 is a plan view of Fig. 1, parts being broken out. Fig. 4 is a vertical longitudinal section of the feed-box 30 on a larger scale. Figs. 5 and 6 are detail side elevations of slotted standards and end views of the receiver guided in the same. Fig. 7 is a detail transverse section of the binder-feeder. Fig. 8 is a detail side view of 35 the stretcher-roller for the rolling-apron. Fig. 9 is an enlarged cross-sectional view of the same. Fig. 10 is an enlarged plan view of the open face of the reversible receiver.

Similar letters of reference indicate corresponding parts.

Referring to the drawings, A represents the supporting-frame of my improved cigar-bunching machine, and is provided with the two upright standards A' for guiding and supporting some of the working parts of the machine. On the table A the bunch-roller mechanism as well as the binder-feeder are mounted, while above the same, supported on standards A², is arranged a horizontal feed-box B. 45 In guides on the standards A' the vertical movable cutting and shaping knife C, with its follower C', the trough D, for receiving the

tobacco-trimmings, and the vertically-reciprocating and reversible receiver E are mounted. The rolling-table F, the rolling-apron F', the 55 horizontal reciprocating slide-plate F², the binder-feeder G, the binder-table I, and the trimming-shears H' are all mounted on the table A.

S represents a driving-shaft, to which rotary motion is imparted by a suitable belt-and-pulley transmission.

The feed-box B has a longitudinal opening and is made of two sections, the top section being hinged or made detachable and secured 65 to the lower section by fastening-pins or suitable devices. The transverse section of the longitudinal opening in the feed-box corresponds to the size and shape of the bunch to be made, the tobacco being placed in the feed-box either in regular layers or mixed with scraps, accordingly as long-filler bunches or bunches with mixed filler are to be made.

The bottom section of the feed-box is provided with a longitudinal slot b, in which is 75 guided an intermittently-moving follower B', of the same shape and size as the longitudinal opening of the feed-box. The follower is provided on the outside of the box B with a forked screw-nut b', which can travel on the 80 screw-spindle B², mounted centrally and longitudinally below the feed-box, which spindle receives intermittent rotary motion from the beveled gears b³ and b⁴, the ratchet-wheel b⁵ on the shaft b⁶, and the pawl b⁷ on the pawl-lever b⁸, mounted to rock on the shaft b⁶. The 85 pawl-lever b⁸ is provided with a pin that enters the upper slotted end of a rod b⁹, the opposite end of which is pivoted on a crank S' of the shaft S, so that when said shaft is rotated the lever b⁹ is worked up and down and in turn rocks the pawl-arm b⁸, whereby the 90 shaft b⁶ and screw-spindle B² are rotated intermittently, and whereby an intermittent forward motion is imparted to the follower 95 B' to cause the same to feed the required quantity of tobacco out of the forward end of the feed-box. The screw-nut of the follower B' is forked, thus permitting of lifting it off the spindle when it arrives at the open end 100 of the feed-box and returning it to the opposite end of the feed-box without reversing the motion of the spindle.

When the required quantity of tobacco has

been fed from the open end of the feed-box to form one bunch, the knife C descends and cuts off the projecting quantity of tobacco and carries it downward. The cutting-knife 5 is made box-shaped with sharp edges and is about the shape of the cigar-bunch, so as to shape the tobacco at the same time as cutting the same. In line with the bottom of the feed-box there is a bracket-plate C², which 10 has an opening corresponding to the shape of the box-shaped knife, said bracket-plate serving to support the tobacco fed from the open end of the feeding-box and offering the required degree of resistance to the cutting and 15 shaping knife. As the knife descends, it cuts through the tobacco resting upon the bracket-plate C², and, as the knife has the shape of a cigar-bunch, it is evident that the pieces cut out by said knife have the shape, approximately, of a cigar-bunch. As the bottom edge 20 of the knife passes through the aperture in the bracket-plate C², it is evident that the knife-edge cuts through all the layers of tobacco resting upon said bracket-plate, thus 25 completely severing the tobacco that is to form the bunch from the remaining part of the tobacco. The tobacco in the box B is compressed quite compactly, so that when the 30 knife or cutter C passes through the same the leaves do not scatter or crumble, but are cut as though the tobacco formed a coherent mass. The trimmings, which consist of the tobacco that remains outside the edges of the cutting-knife, pass into the trough D on the front 35 edge of the bracket-plate C² and are afterward worked up as scraps.

Vertical reciprocating motion is imparted to the cutting and shaping knife C by the pinion d engaging the rack c² on the shank 40 C³ of the cutting-knife, said pinion being actuated by a segmental rack d' on one end of a fulcrumed lever d², which is connected by the connecting-rod d³ with the crank S² of the shaft S, so that with each rotation of the 45 driving-shaft the cutting and shaping knife is vertically reciprocated, so as to descend and cut off the tobacco and move into a position above the feeding-box, so as to be out of the way of the tobacco fed from the end of 50 the same.

The shank C³ of the cutting-knife C is provided with a longitudinal slot or recess for guiding the shank C⁴ of the follower C', which latter is located in the box-shaped knife C 55 and retained in this position by a spiral spring d⁷, attached to the shank C⁴ and to a plate d⁹, fastened to the shank C³ of the knife C. A lever d⁸ engages the upper end of the follower-shank C⁴ and is pivoted to a 60 bracket-arm C⁵ of the knife-shank C³. The outwardly-projecting end of the lever-arm d⁸ can strike against the transverse end of an arm d¹⁰, attached to one of the cross-bars or guides uniting the standards A'. When the 65 knife descends, the outer end of the lever d⁸ strikes against the cross-arm d¹⁰, and at the moment when the knife has completed its

cutting operation the inner end of the lever d⁸ is forced downward and the follower is pressed down, and, overcoming the resistance 70 of the sides of the knife, forces the tobacco out of said knife and into the cup-shaped receiver E, which is located below the opening of the bracket-plate C², ready to receive the tobacco. As soon as the tobacco has been 75 dropped into the receiver E, the same descends, being guided by vertical parallel slots e¹ of the side standards A, as shown in Figs. 5 and 6, the middle slot e' being longer than the side slots e. The receiver is made of a 80 semicircular shape and is formed of two quadrant-sections E', which are pivoted to each other at the ends by the studs e², which pass into the central slots e'. The receiver is provided at each end of each section with a guide-pin e³, and they are guided in the slots. The 85 said side slots e are curved outwardly at their lower ends, which has the effect of opening and reversing the receiver at its lower central line, so that the sections close up again 90 when the inverted position is attained, as in Fig. 6, so that the tobacco can drop from the receiver upon the rolling-apron F'.

Each end pivot e² of the receiver is surrounded by a spiral spring e⁴, said spring 95 serving to keep the receiver closed—that is, in the position shown in Fig. 5. Each section E' of the receiver also contains an adjustable gage e⁵, so as to adapt the receiver for making bunches of different lengths. Each quadrant-section E' of the receiver is provided on the longitudinal edge with a curved extension or wing E⁶, which wings or extensions overlap, as shown in Fig. 4, and prevent the tobacco being caught between the edges of 105 the sections.

Motion is imparted to the receiver by means of fulcrumed angular arms M, which are connected by a transverse rod m at their rear ends, and are provided at their front ends 110 with slots, said slots engaging the projecting pivot-pins e² of the receiver. Spiral springs M' are fastened to studs on the angular arms M and to arms on the vertical standards A and serve to swing the angular arms M upward, whereby the receiver E is held raised 115 in its initial cup-shaped position below the bracket-plate C². The downward motion is imparted to the swinging arms M and receiver E by the action of the cam-shaped projection N on the slide-plate F², which slide-plate receives horizontal reciprocating motion from the shaft S by means of the connecting-rod f, pivoted to the crank S³ of the shaft S. The slide-plate F² is suitably guided on the top 120 side bars of the frame A, so that it can be projected beyond the ends of said side bars. The rolling-table F, which is held between the front parts of said side bars, is mounted on springs to adapt it to give vertically and 125 has its top recessed longitudinally, as shown in Fig. 2—that is to say, the top of the table is provided with a recess extending in the direction of the length of the same, and the 130

profile of said recess corresponding to the contour of one-half of a cigar. The rolling-apron F' is secured at its front end to a stationary roller f' of the rolling-table, is passed over the top edge of the rolling-table below a tension-regulating roller f², the ends of which move in slots in the sides of the slide-plate F², then over a roller F³ of the slide-plate F², and then down to a stationary roller f⁴ of the frame of the machine, to which roller the apron is attached in some suitable manner, said roller being so shaped as to cause the rolling-apron to form a longitudinal recess between its edges. By the forward motion of the slide-plate F² a bight is formed in the rolling-apron, said bight inclosing the filler previously placed upon the apron by the receiver E and rolls the filler on its axis to impart the proper shape to the same, wherein it is assisted by the particular shape of the roller f⁴, (shown in Fig. 8,) which imparts to the apron a shape conforming to the shape of the cigar to be produced. The rolling action takes place in the usual well-known manner. A number of binders are applied one above the other on the binder table or rest I on the front end of the frame A. The binder-feeder consists of a hollow box G, having its top perforated, and is provided with a hollow arm G', having a hub g, that turns on a pivot g' on one of the side bars of the supporting-frame. The tubular arm G' is connected by a flexible tube G² with a suction device consisting of bellows G³, the bottom of which is connected with a pivoted lever G⁴, the opposite end of the lever being connected by a connecting-rod G⁵ with the crank S' of the shaft S. The oscillations of the pivoted lever G⁴ produce the expansion and contraction of the bellows G, thereby producing an inward suction of air through the binder-feeder G or an expulsion of air through the same. A stud h, projecting from one of the sides of the slide-plate F², passes into the longitudinal slot of an arm h' on the hub g, so that the reciprocations of the slide-plate swing the binder-feeder from the rolling-table upon the binder table or rest and back again. At the moment that the perforated face of the binder-feeder arrives at the uppermost binder on the binder-table I the bellows are expanded and the air drawn into the same, whereby the uppermost binder is tightly sucked upon the face of the binder-feeder, and is then carried by the binder-feeder upon the rolling-table F by the returning movement of said binder-feeder. When the binder arrives upon the rolling-table F, the bellows are contracted, whereby the binder is released and can now be rolled around the tobacco in the bight in the apron, the binder-feeder being moved out of the way by the forward motion of the slide-plate F² before said rolling operation takes place. The rolled bunch drops over the end edge of the table into the shears H, each having a fixed blade and pivoted spring-actuated blade H'. As

the roller f³ of the slide-plate passes over the upper ends of the spring-blades H', which upper ends are beveled on the inner edges, it 70 presses them outward and passes beyond them, and when the binder-table makes its return or back stroke the roller f³ catches on the outer edges of the blades H' at the upper ends and presses the said blades H' toward the fixed blades, whereby the ends of the bunches are cut off at the required length. The bunch is then dropped into a suitable receptacle. (Not shown.) At that side of the rolling-table where the head of the bunch is 80 formed is located a paste-supplying sponge L, which is attached to the lower end of the tubular paste-receptacle L', having a funnel on its upper end. The tubular receptacle L' is secured on the end of a pivoted lever K, on 85 one end of which a pin K' on the knife C can act. A spring K², acting on said lever K, serves to keep the sponge in the raised position. When the knife descends, it strikes the end of the lever K, swinging the same outward slightly, and then as the knife rises again it strikes the bottom edge of said end of the lever and swings said lever and the sponge downward, whereby a small quantity of paste is applied on the binder. 95

The machine forms bunches of cigars or cheroots with considerable rapidity and automatically without requiring skilled hands. It can also be used with slight modification for making cigarettes. The motion-transmitting mechanism may be altered, as I do not confine myself to the special mechanism for imparting motion to the follower of the feed-box, the cutting and shaping knife, the follower in the same, the receiver, the horizontal slide-plate, 105 binder-feeder, and bellows. For properly working the machine it is necessary to use dry tobacco in the feed-box, for which purpose the number of feed-boxes are prepared beforehand, the tobacco in the same being 110 compressed so as to assume the shape of the box as it drives.

Having thus described my invention, I claim as new and desire to secure by Letters Patent—

1. The combination, with a stationary feed-box, of a follower within said feed-box for feeding the tobacco from one end of the feed-box, a vertically-reciprocating cutting and shaping knife at the open end of the feed-box, a bracket-plate projecting from the bottom of the feed-box at the open end and having an aperture corresponding to the shape of the cutting and shaping knife, a follower within said knife, a vertically-reciprocating and reversing receiver below said knife and bracket-plate, and a tobacco-rolling mechanism, substantially as shown and described, below said receiver, so as to adapt it to receive the tobacco discharged from said receiver, substantially as set forth. 120 125 130

2. The combination, with a feed-box, of a follower within said box for discharging the tobacco out of one end of the feed-box, a bracket-plate projecting from the bottom of

the feed-box at the open end, which bracket-plate has a cigar-shaped aperture, a trough for the scraps adjacent to said bracket-plate, a vertically-reciprocating cutting and shaping knife above said bracket-plate, a follower within said cutting-knife, a vertically-reciprocating and reversing receiver below the bracket-plate, and a rolling mechanism below the vertically-reciprocating receiver, substantially as set forth.

3. In a cigar-bunching machine, the combination, with a rolling mechanism, substantially as described, of a tobacco feed-box, a follower in said feed-box, a vertically-reciprocating cutting and shaping knife at one end of the feed-box, an apertured bracket-plate below said cutting and shaping knife, a vertically - reciprocating and reversing receiver below said bracket-plate, and a pasting apparatus operated from said vertically-reciprocating knife, substantially as set forth.

4. In a cigar-bunching machine, the combination, with a feed-box, of a follower in the same, a vertically-reciprocating cutting and shaping knife at one end of the feed-box, a bracket-plate at the end of the feed-box, provided with an aperture below the knife, said aperture having the same shape as the knife, a vertically - reciprocating and reversing receiver below said bracket- plate, a rolling mechanism below said receiver, and levers actuated by the rolling mechanism and operating said receiver, substantially as set forth.

5. In a cigar-bunching machine, a reversible receiver composed of two quadrant-sections pivoted to each other at their ends and provided on both longitudinal edges with overlapping wings, substantially as set forth.

6. In a cigar-bunching machine, the combination of a reversible receiver composed of two quadrant-sections pivoted to each other at their ends and provided with guide-pins

projecting from the ends with vertical guides having guide-slots for receiving the pins projecting from the ends of the reversible receiver, substantially as set forth.

7. In a cigar-bunching machine, the combination, with vertical standards each having a central longitudinal slot and two side slots, the lower ends of which are curved outward, of a tobacco-receiver composed of two quadrant-sections pivoted to each other at their ends, the pivot-pins of the receiver sliding in the central longitudinal slots of the standards, pins projecting from the ends of the pivoted sections sliding in the side longitudinal slots, and a lever for raising and lowering said receiver, substantially as set forth.

8. In a cigar-bunching machine, the combination, with two quadrant-sections pivoted to each other and forming a tobacco-receiver, of a transverse partition in said receiver, which partition is adjustable in the direction of the length of the receiver, substantially as set forth.

9. In a cigar-bunching machine, the combination, with a vertically-adjustable table for receiving the binder-leaves, of a rolling mechanism mounted to reciprocate toward and from said binder-table, a fixed rolling-table over which the reciprocating rolling mechanism can pass, and a swinging binder-feeder mounted to swing from the binder-table upon the rolling-table, which binder-feeder is connected with and operated by the reciprocating rolling mechanism, substantially as set forth.

In testimony that I claim the foregoing as my invention I have signed my name in presence of two subscribing witnesses.

CARL H. HAUGK.
